B. SEWALL.

CAN FILLING MACHINE.

No. 250,172.

Patented Nov. 29, 1881.

UNITED STATES PATENT OFFICE.

BRADFORD SEWALL, OF FARMINGTON, MAINE.

CAN-FILLING MACHINE.

SPECIFICATION forming part of Letters Patent No. 250,172, dated November 29, 1881.

Application filed July 5, 1881. (Model.)

To all whom it may concern:

Be it known that I, BRADFORD SEWALL, of Farmington, in the county of Franklin and State of Maine, have invented an Improved 5 Can-Filling Machine, of which the following is a specification.

The object of my invention is to provide a new and improved machine for filling cans rapidly without any waste, and which feeds and 10 carries off the cans automatically.

The invention consists in a can-filling machine composed of a table on which a radially-winged wheel is pivoted, between which wings the cans pass from the lower end of an open 15 cylinder containing a stock of cans, and are carried under the nozzle of a cylinder, which is held in a raised position by a weight attached to the outer end of a lever acting on the cylinder-frame, and in which cylinder a piston 20 fits, which is suitably guided and actuated by a rod connected with a lever, to which a sliding bar is also connected, sliding under the table, and provided with a pawl, which rotates the can-carrying wheel.

25 In the accompanying drawings, Figure 1 is a plan view of my improved can-filling machine. Fig. 2 is a longitudinal sectional elevation of the same on the line xx , Fig. 1. Fig. 3 is a cross-sectional elevation of the same on the line yy , Fig. 1. Fig. 4 is a cross-sectional elevation of the same on the line zz , Fig. 1.

Similar letters of reference indicate corresponding parts.

A wheel, A, provided with a series of radial 35 wings, B B, is pivoted to rotate in a horizontal plane on a table, C, under which a bar, D, slides, provided with a pawl, E, which catches on the wings B B, and thus rotates the wheel A. The rear end of the sliding bar D is pivoted 40 to an upright arm, F, of a swinging lever, G, attached to a transverse bar, H, pivoted in the frame of the machine. The lever G is provided at its front end with a handle, J, for operating it. A rod, K, attached to the lever G, extends upward, is bent at right angles, and 45 passes into an aperture in the piston-rod L, which is guided to slide vertically on the transverse bars M of the upright frame of the machine. A piston, N, is attached to the lower 50 end of this piston-rod L and fits in a cylinder, O, provided with a downward-projecting spout

or nozzle, P, which fits into apertures in the cans Q. The cylinder O is attached to a frame, R, sliding and guided on the upright part of the frame of the machine. The lower end of 55 a board or bar, S, extending downward from the frame R, is pivoted to a pivoted lever, T, having a weight, U, attached to its outer end, which weight serves to hold the frame R and the cylinder O in a raised position. A number of cans, Q, are held one above the other in a vertical cylinder, V, of any desired height, and attached to the vertical part of the frame of the machine in such a manner that the cans, passing from the lower end of this cylinder V, 60 will pass in between two wings B B of the wheel A.

The table C is provided with a series of apertures, W, through which the waste material drops.

70 The guard-plate Y prevents the cans from being forced from the table and forms a curved track, along which the cans slide.

The operation is as follows: If the handle J is raised the piston N is drawn out of the cylinder O and the pawl E moves the wheel A in the direction of the arrow a' . One of the wings rests against the lowest can Q of the column of cans in the cylinder V and carries it along, thus causing all the cans in the cylinder V to 80 drop the distance of one can, and the cans will be thus successively carried off by the wheel A. The cans are thus carried under the cylinder O, into which the material that is to be filled 85 into the cans is passed. By depressing the handle J the plunger or piston N is pressed into the cylinder O, and the cylinder is thus lowered, the spout or nozzle P passing into an aperture in the top of the can. By further depressing the handle J the piston forces all the 90 material from the cylinder into the can. If the handle is raised an empty can is carried under the cylinder and the filled can is carried away and thrown outward by the wheel A. As the weight U raises the cylinder O as soon as the 95 piston is raised, the wings B cannot strike against the lower end of the spout P.

Having thus described my invention, I claim as new and desire to secure by Letters Patent—

1. In a can-filling machine, the combination, 100 with the table C, of the guard-plate Y and the wheel A, provided with radial wings B, sub-

stantially as herein shown and described, and for the purpose set forth.

2. In a can-filling machine, the combination, with the table C, of the guard-plate Y, the wheel A, provided with radial wings B, the can-receiving cylinder V, the cylinder O, the piston N, the rod K, the levers G and T, the weight U, the bar D, and the pawl E, substantially as herein shown and described, and for the purpose set forth.

3. In a can-filling machine, the combination, with the piston N and cylinder O, of the rod K, the levers G and T, the frame R, and the strip or bar S, and the weight U, substantially as herein shown and described, and for the purpose set forth.

4. In a can-filling machine, the combination, with the table C, of the guard-plate Y, the wheel A, provided with radial wings B, the can-receiving cylinder V, the cylinder O, the piston N, the rod K, the levers G and T, the weight U, the bar D, and the pawl E, substantially as herein shown and described, and for the purpose set forth.

BRADFORD SEWALL.
